UNITED STATES PATENT OFFICE.

JOHN E. MANN, OF SNOHOMISH, WASHINGTON.

ROAD MAP AND WINDING MECHANISM THEREFOR.

Application filed February 16, 1925. Serial No. 9,609.

This invention relates to improvements in road maps and winding mechanism therefor; more particularly to mechanism of that character especially designed for attachment to the instrument board of an automobile and wherein the map is made up in strip form and is adapted to be wound on rollers and to be advanced, as required, beneath a glazed opening in the housing.

The principal object of this invention resides in the provision of a device of the above stated character wherein there are two map mounting rollers from and onto which the map may be wound and which are both operable from the same drive wheel, through a novel driving mechanism which provides for driving only the roller on which the map is being wound and without driving the other roller, thus avoiding the difficulty that would otherwise be experienced on account of the variation in sizes of the two rolls as the map is wound back and forth.

In accomplishing these and other objects of the invention, I have provided the improved details of construction, the preferred forms of which are illustrated in the accompanying drawings, wherein—

Figure 1 is a front elevation of a road map housing and winding mechanism embodied by the present invention.

Figure 2 is a sectional view of the same particularly illustrating the mounting of the map on the two winding rollers, and the means whereby they are driven.

Figure 3 is a sectional view taken just within the side wall substantially on the line 3—3 of Figure 2.

Figure 4 is an end view of one of the rollers and its winding wheel; showing the pawl carried by the latter and the notch in the roller for receiving the pawl.

Referring more in detail to the drawings—

1 designates, in its entirety, a housing in which the road map and winding mechanism is contained and comprising a back wall 2 having upper and lower end portions 3 extended beyond the ends of the housing and provided with openings 4 for receiving screws or bolts 5 whereby it may be mounted on the instrument board of an automobile or similar vehicle. The left hand side of the housing is closed by a wall 6 cast integrally with the back and upper and lower end walls 7 and 8 respectively, and the opposite side is closed by a removable

door 9 provided at its lower edge with a rib 10 adapted to seat within a groove 11 in the edge of the base wall and having a clip 12 fixed to its upper end for engagement with a stop or shoulder 13 on the top wall to thereby hold the door in place.

The front of the housing is closed by a wall 14 provided with an elongated opening 15 in which a transparent panel 16 of glass or other suitable material is fitted and through which the map may be observed.

Located in vertically spaced apart, parallel relation within the housing are two rollers 17 and 18 on which the map strip or web 19 is wound. These rollers have trunnions 20 at their ends freely rotatable in openings 21 in the side walls 6 and 9 and have slots 22 formed longitudinally in their central portions for receiving the ends of the web so as to prevent it slipping during a winding operation. There are also two small guide rollers 23 and 24 mounted in a similar manner between the side walls closely to the upper and lower ends of the opening 15 over which the strip is guided while being wound from one roller to the other and which support the web closely to the glazed panel where it can be easily seen.

The means which I have provided for winding the strip back and forth between the rollers comprises a wheel 26 that is fixed on the inner end of a short shaft 27 that is extended rotatably through a bearing 28 opening 28 in the side wall 6 at a point midway of the ends of rollers 17 and 18 and which has a winding crank 29 fixed to its outer end. Mounted rotatably on the ends of rollers 17 and 18 and frictionally engaging the upper and lower edges of wheel 26 are relatively small wheels 30 and 31, each of which has a pawl 32 pivotally fixed to its outer face and adapted to be pressed by springs 33 into notches 34 formed in the rollers so as to provide a one way driving connection between the wheels and their rollers; the pawl being so arranged that they will effect the winding of the web onto the rollers but will permit the wheels to rotate freely on the rollers where it is being unwound therefrom.

It is intended that the map strip be made of a transparent or semi-transparent material and that an electric light, as designated at 36, be located on the base within the housing and provided with a reflector 37

which will cause the strip to be illuminated so that the map may be easily seen at night.

It is the intention, to provide road maps in strip form either from photographs taken from an aeroplane or from surveyor's maps and to lay them out to an exact scale so that, if it is so desired, a mechanical means may be used to operate the winding mechanism. Such would consist, preferably, of a gear 10 wheel 40 fixed to the shaft 27 and adapted to be driven, after removal of crank 29, by connection with a wheel of the vehicle or from the speedometer by a driving gear and shaft as designated at 41 in Figure 1.

15 It is readily apparent that devices of this character could be made up in various sizes, shapes and in designs suitable for different vehicles, and that various details of construction could be made without departing 20 from the spirit of the invention. It may be desirable to use toothed gears in place of the smooth surfaced wheels 26, 30 and 31.

Having thus described my invention, what I claim as new therein and desire to secure 25 by Letters-Patent, is:

1. A device of the character described, comprising a housing provided with a front opening, a pair of rollers mounted in the housing on which a strip may be wound and advanced from one to the other closely beneath said opening; said rollers having pawl receiving notches therein, a winding shaft 30 rotatably mounted in a side wall of the hous-

ing, a wheel fixed on the inner end of said shaft, a crank fixed to the outer end thereof, winding wheels rotatably mounted on said rollers in frictional driving contact with said wheel, pawls pivotally fixed to said winding wheels and engageable with the rollers to effect a winding connection, but 35 permitting free rotation of the wheel on the roller from which the strip is being unwound.

2. A device of the character described comprising a housing provided with a front 40 opening, a pair of rollers mounted in the housing on which a strip may be wound and advanced from one to the other closely beneath said opening; said rollers having pawl receiving notches therein, a winding shaft 45 rotatably mounted in a side wall of the housing, a wheel fixed on the inner end of said shaft, a crank fixed to the outer end thereof, winding wheels rotatably mounted on said rollers in frictional driving contact with 50 said wheel, pawls pivotally fixed to said winding wheels and engageable with the notches of the rollers to effect a winding connection, but permitting free rotation of the wheel on the roller from which the strip is 55 being unwound and a lamp located in the housing to illuminate the strip beneath said opening.

Signed at Everett, Snohomish County, Washington, this 23rd day of January 1925.
JOHN E. MANN.
